UNITED STATES PATENT OFFICE.

WILLIAM GLASGOW, OF CHICAGO, ILLINOIS.

MACHINE FOR ENAMELING OR PREPARING MOLDINGS FOR GILDING.

SPECIFICATION forming part of Letters Patent No. 226,845, dated April 27, 1880.

Application filed November 25, 1879.

To all whom it may concern:

Be it known that I, WILLIAM GLASGOW, of Chicago, in the county of Cook and State of Illinois, have invented a new and valuable Improvement in Machines for Enameling or Preparing Moldings for Gilding; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a top-plan view of my invention. Fig. 2 is an under-side plan view. Fig. 3 is a perspective view on a reduced scale. Fig. 4 is a detail view of one of the pressure-rollers. Fig. 5 is a detail view of one of the sides forming the composition-box and supporting-bracket; and Fig. 6 is a cross-section of the frame, showing an end view of one of the composition-boxes, with its brackets, and end view of the tracks, with means for adjusting them.

This invention has relation to improvements in that class of machines employed for the purpose of filling the pores of wood moldings and other strips or pieces of wood with a suitable composition in order to render them in a condition for gilding, polishing, varnishing, &c.

The object or purpose of the invention is to provide a machine of the above character that will prepare the molding for gilding by covering the same with a suitable composition in a perfect and rapid manner, with the economy of time and labor, and, further, to generally improve and simplify the machine in its details of construction.

To these ends my improvement consists in certain peculiar constructions and arrangements of the several essential parts co-operating to render the machine successful in its purpose; also, in the novel combination of devices which will be fully and comprehensively explained and described hereinafter, and specifically designated or pointed out in the claims.

In the accompanying drawings, A represents a frame, preferably of rectangular form, and supported by suitable legs a. The frame A has secured to it, near one end thereof, a table, B, of metal or other suitable material,

adapted to be lowered or raised from the frame, for the purpose hereinafter described.

The table B supports gages C to guide the molding in its course to the composition box or boxes, said gages being laterally adjustable by bolts and nuts passing through elongated slots in the table to widen the space between and adapt the gages to various widths of molding.

To the frame A are secured one or more slotted arches, D, which support boxes b, said boxes being adjustable within the slotted arch and held at the desired position by screw-bolts and nuts.

Passing through the boxes b are holders c, having secured to their lower ends rollers E, said holders being vertically adjustable within the boxes by a screw-rod, d.

The arches D may each have several rollers, with their attachments, as would be frequently required in operating upon moldings of various designs, and the vertical adjustment of the rollers, as well as their adjustment within the arc of a circle, adapts them to be used with various classes of molding, the rollers being set at any angle and height required. As these rollers should bear upon the surface of the molding with a certain amount of pressure, and at the same time not injure the composition thereon, in order to hold the molding in position as it is passing to the composition box or boxes, the rollers are composed of rubber or other similar elastic material, whereby they can press on the molding with the required force without danger of injuring the composition, as it should be understood that the molding passes through the machine several times in order to give it a series of coatings or layers of composition.

Heretofore these slotted arches employed in this class of machines were for the purpose of supporting rubbers which pressed the preparing material into the pores of the wood and removed the surplus material from the moldings. These rubbers were adjustable within an arc of a circle or within the slots of the arches, and also were vertically adjustable by screws and nuts; but the function or purpose of the rubbers was not analogous to that of the elastic rollers E, the same, as previously

stated, being to guide and keep the molding in proper position and in contact with the feed-rollers N.

Secured to the frame A forward of the table 5 B are the boxes for containing the composition, of the kind usually employed for coating wood moldings. These composition-boxes consist of two sides, F G, supported by brackets H, being laterally adjustable upon the frame; 10 or, if desired, one only of the brackets may be adjustable by a set-screw, e, passing through the elongated slot f in the base of the bracket, for adjusting the sides F G to or from each other, for the purpose of adapting the width of 15 the boxes to the varying widths of the molding. Upon the outer faces of the sides F G are lugs g, with screw-threaded openings therein to receive tension thumb-screws h, the lower ends of which engage with similar lugs i on 20 the sides of the brackets H. A coil-spring, k, passes around each of the thumb-screws h, and is disposed between the lugs g i, for the purpose of relieving the molding as it passes through the composition-boxes from the weight 25 of the sides F G, and thereby insuring the desired quantity of composition to be deposited on the surface of the molding both evenly and smoothly, which would not be the case were the sides of the composition box or boxes not 30 properly supported. The tension of the springs k is regulated by the screws h to elevate or depress the sides F G, as circumstances may require.

The thumb-screws h above the lugs g are 35 provided with shoulders l, and between the shoulders and lugs are rubber or other suitable springs m, so as to render the boxes or sides thereof yielding in a vertical direction, so as to accommodate them to the increased 40 thickness of the molding caused by the several coatings or layers of composition thereon as it enters the boxes, thereby insuring a better and more uniform coating, which is indispensable in a perfect operating machine.

45 The sides F G are independent of the brackets H, and are provided upon their outer faces with vertical grooves n, which engage with shoulders o of the brackets H, to steady and guide the sides in their vertical adjustment. 50 The sides are slotted, as shown at p, to receive templets I, held therein by suitable set-screws q. These templets are in form and shape to correspond with the form and shape of the molding, and they may be removed, and others 55 of different patterns secured in their place, as required. The interior surfaces of the sides F G are provided with longitudinal shoulders r, which serve to guide the molding through the boxes, so that the molding forms a traveling bottom for the boxes, and receives its coating therefrom.

Secured to the frame A, and upon each side thereof, are scrapers K, of steel or other suitable metal, and which may be adjustable to 65 suit or adapt them to moldings of different widths, and may also be detachable from the

frame, and replaced by others of different shape, as required by the special design of the molding that is being coated.

The scrapers K have sufficient elasticity to 70 perform their office in scraping or removing the composition from that portion of the molding where it is not required.

To the under side of the frame A, and across the same, are secured bridges L, which support tracks M at right angles thereto, or length-wise of the frame A, to support the molding within the composition-boxes and while passing through the same. These tracks M have screw-threaded rods upon their under side, 75 which pass through elongated slots in the bridges L, by which arrangement the tracks are adjustable to or from each other and held at the desired distance apart by suitable nuts upon the screw-rods bearing against the under 80 side of the bridges, and also elevated or lowered by the addition of a nut upon the upper side of the bridge, as shown in Fig. 6. This lateral or horizontal adjustment is for the purpose of increasing the width between the tracks to 85 accommodate them to the width of the molding being coated.

The vertical adjustment of the tracks M is 90 to compensate for the wearing away of the peripheries or faces of the feed-rollers.

The feed-rollers N, upon the under side of the table B, are composed of rubber, having their shafts t in suitable bearings in the sides of the frame A, and the rollers are rotated by suitable gear-wheels P Q, attached to the ends 100 of the shafts t and communicating motion to each other by a pinion, u, motion being imparted by a drive or other suitable wheel, R. Any well-known means, however, may be employed to impart the desired rotary motion to 105 the rollers N, either by hand or other suitable power. The rollers N pass up through openings in the table B, so as to have their periphery above the upper surface thereof, to bring the rollers in contact with the under side of 110 the molding, thereby causing the molding to be forced or carried along to the composition-boxes to receive its coating. The rubber rollers N, by continued contact with the under surface of the wood molding, wear away to 115 such extent that the periphery of said rollers will no longer come above the table B, and the consequence would be that the rollers would not act to feed along the molding to the composition-boxes. Provision, however, is made 120 for this wearing away of the feed-rollers by the vertical adjustment of the table, which is accomplished by set-screws w. It will therefore be seen that as the feed-rollers N wear away, the table B, with its gages C, is lowered 125 sufficiently to have the rollers come above the surface of the table to operate upon the molding.

It should be noticed that the tracks M are also vertically adjustable to bring them on the 130 same plane as the table B, and the rollers E are directly over the feed-rollers N, so that

the molding upon its upper surface is pressed down with sufficient force to insure the perfect operation of the rollers N upon the molding.

5 When a special form of molding is to be coated the templets I are replaced by others of the required form, and secured by the set-screws q within the slotted ends of the sides F G, the sides being first adjusted to conform 10 to the width of the molding, as are also the gages C and tracks M. The molding is now placed between the gages C, and is fed along by the rollers N to the boxes, which are filled with any of the well-known compounds usually employed for preparing moldings for gilding.

15 The manner of supporting or connecting the sides of the composition-boxes to the brackets H, and at their forward ends only, admits of their rising automatically to allow 20 of the molding passing under the templets I.

In order to give the required evenness or smoothness to the surface of the composition and have it of the requisite thickness upon 25 the molding, the latter is passed through the machine a number of times until it receives a sufficient number of layers or coatings of the composition to produce the effect desired, the scrapers K, as the molding passes along, removing therefrom the surplus composition.

30 The composition-boxes, slotted arches, and the pressure-rollers connected thereto, also the feed-rollers, may be multiplied or increased in number, as found desirable.

35 Having now fully described my invention, what I claim as new, and desire to secure by Letters Patent, is—

1. In a machine for enameling or preparing moldings for gilding, the combination, with 40 the feed-rollers N, having their journals in the stationary frame A, of the table B, having openings through which pass the peripheries of the rollers, said table being vertically adjustable with relation to the position of the 45 rollers, substantially as and for the purpose set forth.

2. The frame A, having journaled therein feed-rollers N, in combination with the table B, having openings to receive the peripheries 50 of the rollers, said table being vertically adjustable with relation thereto, and carrying

laterally-adjustable gages C, substantially as and for the purpose set forth.

3. The slotted arches D, having adjustably secured thereto boxes b, in combination with 55 the holders e, carrying rollers E, and the screw-rod d, for adjusting the holders, substantially as and for the purpose specified.

4. The combination, with the laterally-adjustable brackets H, of the movable sides F 60 G and templets I, substantially as and for the purpose described.

5. The sides F G of the composition-box, secured by a vertically-yielding attachment, substantially as described, to the adjustable brackets H at one of their ends only, so as to admit of their tipping or rising at their free ends to accommodate the templets to the varying thickness or irregular surface of the molding, substantially as and for the purpose 70 specified.

6. The combination, with the brackets H and sides F G of the composition-box, of the tension screw-rods h and the springs h m, for rendering the box yielding to the inequalities 75 of the surface of the molding, substantially as and for the purpose specified.

7. The combination, with the vertically-adjustable table B, of the vertically and laterally adjustable tracks M, arranged under the 80 composition-boxes, substantially as and for the purpose described.

8. The composition-boxes composed of the laterally-adjustable sides F G and the templets I, in combination with the vertically and 85 laterally adjustable tracks M, substantially as and for the purpose specified.

9. The frame A, having journaled thereto the feed-rollers N, and the independent vertically-adjustable table B, carrying adjustable 90 gages C, in combination with the adjustable rollers E, adjustable tracks M, and adjustable sides F G of the composition-boxes, substantially as and for the purpose set forth.

In testimony that I claim the above I have 95 hereunto subscribed my name in the presence of two witnesses.

WILLIAM GLASGOW.
